ELECTRIC SIGNALING, SUPERVISING, AND RECORDING SYSTEM

James R. Harrington, Mansfield, Ohio, assignor, by mesne assignments, to The Autocall Company, Shelby, Ohio, a corporation of Ohio

Application February 8, 1936, Serial No. 62,913

10 Claims. (Cl. 234—27.5)

The present invention relates to electric signaling, supervising and recording systems of the type characterized by a plurality of control boxes or transmitters interposed at different points in a connecting circuit and so arranged that when an alarm or like condition arises at or in the vicinity of one of these boxes, or when a change occurs in the condition of certain apparatus being supervised by the system, or when one of the boxes is manually energized, the system will function to give a signaling or supervisory indication through the energization of notification means. This notification means preferably comprises: (1) audible signaling means, such as signaling bells or the like, which audibly designate the particular box which has been energized in the system and the condition existing at that box; and (2) a recorder which makes a permanent record designating the particular box and the condition which gave rise to the energization of that box. This notification means may include visual indicating means in the form of a flashing light, and/or a series of numeral or character wheels which are given a set-up to designate visually the particular box then operating and the condition which gave rise to the energization of that box.

The present invention embodies improvements on the Electrical signal system disclosed in my prior Patent No. 1,950,108, granted March 6, 1934.

The present invention is also a continuation, in part, of my prior Patent 2,164,324, issued July 4, 1939, on Electric signaling, supervising, and recording systems.

Apparatus of the present type has application to sprinkler alarm systems, supervisory systems, fire alarm systems, burglar alarm systems, watchmen's call systems, and other analogous systems where it is desired that a certain condition or operation occurring at any one or more points along a circuit shall give an alarm or signal indication, or shall exercise a supervisory or regulating indication or control in connection with apparatus associated with the signal system. The system forming the subject matter of the present application embodies certain improvements which are particularly adapted to the fire prevention apparatus of a building or buildings, including means for indicating when any branch or sprinkler head of a sprinkler system is operating; for indicating when the air pressure on a pressure fed water supply system is high or low, or when the water level, as of a gravity fed system, is high or low; for indicating when any of the main control valves of the

sprinkler system are open or closed; for indicating when the power, as of an electrically operated pump, is available or has been interrupted; for indicating when room temperatures rise excessively; for indicating the watchman's calls at each of the watch call stations; or for indicating other conditions having to do with a fire prevention system. Accordingly, I shall describe the invention in such situation, but it will be understood that the fundamental features of the invention can also be embodied in other systems and situations where like signaling and supervisory functions are to be exercised.

One of the objects of the invention is to provide an improved signaling system including improved means for recording the different operations of the system. More specifically, the recording apparatus makes a record of each alarm or supervisory indication, designating the particular box or boxes from which the indication was transmitted, the condition at that box which gave rise to the indication, and preferably the date and time of day when the indication was transmitted. Such record is permanently printed on a sheet, or preferably a continuous paper tape, so that it affords an instantaneous visual indication of the particular box operating and the condition at that box. Such a record can be readily checked for past performance of the system, and is also of value for building maintenance and supervisory data.

Other objects and advantages of the invention will appear from the following detail description of a preferred embodiment thereof. In the accompanying drawings illustrating such embodiment—

Figures 1, 1A, 1B, and 1C are related parts of a complete circuit diagram of one form of my improved system. Figures 1 and 1A, when joined end to end, represent the line portion of the system including the signal boxes. Figures 1B and 1C, when joined end to end, represent the central station circuits and apparatus. The entire system is illustrated complete when Figures 1 and 1A, joined end to end, are placed along the left margin of Figures 1B and 1C, joined end to end.

Figure 2 is a fragmentary front view of the recording apparatus, the major portion of the casing being broken away to illustrate certain operating parts;

Figure 3 is a fragmentary plan view of the same, with the top part of the casing removed;

Figure 4 is a transverse sectional view taken approximately on the plane of the line 4—4 of 55

Figure 2, and looking in the direction indicated by the arrows;

Figure 5 is a transverse sectional view taken approximately on the plane of the line 5—5 of Figure 2;

Figure 6 is a somewhat similar view taken on staggered planes between the planes 4—4 and 5—5 of Figure 2;

Figure 7 is an end elevational view of one of the type wheels, showing the return spring which restores the wheel to its normal position;

Figure 8 is a detail sectional view taken approximately on the plane of the line 8—8 of Figure 6, showing the gear mechanism which transmits motion from the condition type wheel to the selector switch which controls the energization of the general alarm bells and the summary indicator; and

Figure 9 is a detail sectional view showing the pawl apparatus which advances the roller parts feeding the paper tape.

Referring first to Figures 1, 1A, 1B, and 1C, the main operating units of the system consist of a series of signal boxes or transmitters A, B, C, D, E, F, G, etc., and a central station, generally indicated at X, this central station comprising a grouped arrangement of apparatus for performing several functions, such as recording the impulses transmitted from the boxes, transmitting the intermittent current impulses over the circuits, maintaining the circuits under continuous test, and various other functions. While Figures 1 and 1A only illustrate ten boxes A, B, C, etc., it will be understood that any number of boxes or transmitters may be included in the system, depending upon the number of locations or operating stations from which an alarm or supervisory indication is to be transmitted. The entire group of boxes is connected in series relation in circuits defined by three conductors P, N, and S. For facility of explanation, the conductors P—N may be regarded as constituting a "box operating circuit" and the conductor S may be regarded as constituting a "signaling circuit." When Figures 1, 1A, 1B, and 1C are placed in juxtaposition in the manner above described, it will be noted that these three conductors loop back from both ends of the series of boxes to the central station X. The explanation of the entire system will be most easily understood if we assume the boxes, recorder, summary indicator, etc., to be operating on direct current with certain conditions of polarity or directions of polarity feed, as this will enable the circuits to be traced through with respect to positive and negative. However, the same operation occurs when the system is operating on alternating current, and accordingly, it will be understood that where I refer to "positive" and "negative" in this description and in the appended claims, I am not using these terms in a limitative sense, but only for the purpose of differentiation and to facilitate understanding the invention. The system might be operated entirely off an electric lighting or power circuit, but it would then be fallible because of the possibility of interruptions in the source of supply transmitted through the service line, and to avoid this possibility I prefer to employ a battery 50 (Figure 1B) for performing the primary duties of operating the signal boxes, recording the signals, etc., this battery being floated across any suitable type of charging means. For illuminating the trouble lights, sounding the trouble bell and performing various other secondary duties at central station, I preferably employ

current from an ordinary lighting circuit, represented by the two buses 51 and 52 leading from a conventional 110-volt lighting circuit supplying either alternating or direct current. However, the same battery 50 or a separate battery 5 might be employed for supplying current to the trouble bell and lamp power circuit 51—52.

From the positive pole of the battery 50, positive polarity is conducted through the fuse 53 to a positive battery bus designated p. From the opposite pole of the battery, negative polarity is conducted through fuse 54 and is impressed on one terminal of an overload circuit breaker 55. This circuit breaker may be of any conventional type designed to protect the system against destructive short circuits and need not be described in detail. From the other terminal of the circuit breaker negative polarity is transmitted through two branch paths defined by the two negative battery buses n and n'. The first negative battery bus n continues through ammeter 57 and through winding 59 of "full-cycle" control relay 58. The second negative battery bus n' affords a source of negative polarity which does not go through the full-cycle control relay 58. Hence, any circuits which are completed through the first negative battery bus n must have their entire current flow go through the full-cycle control relay 58, whereas any circuits which are completed through the second negative battery bus n' do not have their current pass through this relay. The armature 62 of said relay, upon being moved to its fully attracted position, closes a circuit through the two contact springs 63. A wire 64 connecting with positive battery bus p impresses positive polarity on one of these contact springs, and an oscillator control bus 65 connects to the other contact spring. The relay is so adjusted that the relatively small testing currents normally flowing out over the box operating circuit P—N and over the signal circuit S do not attract the armature 62 to its circuit closing position. However, should a fault occur in the system, resulting in the accidental energization of the recorder, as will be later described, a sufficiently larger current flows through the relay 58 to attract the armature 62 to its circuit closing position, thereby impressing positive polarity through wire 64 and contact springs 63 on the oscillator control bus 65. This causes energization of the oscillator, as will be later described.

A volt-meter 66 is connected between the positive battery bus p and the second negative battery bus n', for showing the voltage of the battery. Any suitable low-voltage alarm apparatus may be associated with the battery 50 for giving an alarm indication if the voltage of the battery should drop below a predetermined minimum.

To avoid the presence of confusing cross-connections in the circuit diagrams of Figures 1B and 1C, the positive battery bus p and the first negative battery bus n have been extended down along the righthand side of the central station apparatus and have then been looped upwardly adjacent to the bank of relays at the lefthand side, this being purely for clarity of illustration.

The supply of current to power buses 51 and 52 from the 110 volt circuit is indicated by the illumination of a pilot lamp 86 connected across the two buses. The extinguishing of this lamp indicates that the power supply to said buses has failed.

A ground test relay 88 may be provided to detect any accidental ground on any of the circuits supplied from the battery 50, this relay oper-

ating to energize the trouble lamp 101 and the trouble bell bus 51'. The operation of such ground test relay is fully disclosed in my Patent No. 2,164,324 of July 4, 1939.

5 Referring now to the positive and negative conductors P and N of the box operating circuit, the positive conductor P can be regarded as starting from a central station terminal designated PL, the latter signifying positive "line." A wire
10 111 conducts positive polarity from the positive battery bus p to the terminal PL. From here the positive polarity is fed through conductor P in a direction extending down through boxes A, B, C, D, etc., in the order named, and is thence
15 conducted back to a terminal at central station which is designated PR, signifying positive "return." It will be observed that this corresponds to a counterclockwise direction in which the positive polarity is fed down through the series of
20 boxes, or is fed through the loop of the box operating conductor P. The non-interfering characteristics of the boxes or transmitters can be best described and understood by referring to the manner in which the polarities themselves are
25 26 "fed" to the boxes, aside from the actual direction of current flow, and accordingly I shall hereinafter refer to the order or manner in which the "polarities" are "fed" to the boxes in the box operating circuit P and N. For clarity, I shall
30 31 also refer to feeding the positive polarity "downwardly" through the boxes (in a direction from box A to box B, etc.) and shall refer to feeding the negative polarity "upwardly" through the boxes (from box J to box I, etc.) but it will be
35 36 understood that these directional terms only have reference to the diagrams and not to any particular direction that the circuits may take in an actual installation. The negative conductor N may be regarded as starting from the central
40 41 station terminal NL, signifying negative "line." Negative polarity is supplied to this terminal from the first negative battery bus n through the following connections: from battery bus n through wire 113 to one of the terminals 115,
45 46 115' of the mercury tube 116 constituting the switch element of the oscillator 114; from the other terminal 115' of this mercury tube through wire 121 to one terminal of an overload circuit breaker 122 of any conventional type designed
50 51 to protect the box operating circuit against destructive short circuits; and from the other terminal of this circuit breaker through wire 123 leading to the negative line terminal NL. From here the negative polarity is fed through conductor N in a direction extending up through the series of boxes J, I, H, G, etc., in the order named and is thence conducted back to the central station terminal NR, signifying negative "turn." It will be observed that such corresponds
55 56 in the diagram to a clockwise direction of impressed negative polarity on the series of boxes or on the loop of box operating conductor N.

The positive return terminal PR is connected through wire 124 to one end of the winding of a 65 positive line test relay 125. A wire 126 extends from the other terminal of the relay winding for connection with the wire 123 which, as before described, has negative polarity impressed thereon from first negative battery bus n through oscillator 114 and overload circuit breaker 122. Under normal, non-signaling conditions the conductor P constitutes a continuous loop, and, hence, it will be seen that a small testing current will normally flow through wire 111 out over the 70 conductor P in a downward direction through the 75

series of boxes and back through the winding of positive line test relay 125 and thence through conductors 123, 121 and 113 back to first negative battery bus *n*. The negative return terminal NR is connected through wire 127 with one end of the winding of a negative line test relay 128. The other end of this relay winding is connected through wire 129 with the wire 111 which connects in turn with the positive battery bus *p*. Under normal non-signaling conditions, the negative conductor *N* is also a continuous loop and, hence, under these conditions a small testing current will be passed continuously through this loop, the negative polarity thereof being fed through wires 113, 121 and 123 to terminal NL, thence through conductor *N* in a direction extending upwardly through the series of boxes and back to negative return terminal NR, and thence through wire 127, winding of negative line test relay 128, wire 129, and wire 111 back to positive battery bus *p*. Inasmuch as the negative polarity for the box operating circuit is drawn from the first negative battery bus *n*, it follows that all current supplied to the box operating conductors *P* and *N* necessarily flows through the winding of the full-cycle control relay 58. As previously remarked, said relay is so adjusted that the relatively small testing currents flowing through conductors *P* and *N* do not attract the armature 62 to circuit closing position, but faults on the system causing the accidental energization of the recorder will cause a greater current flow to pass through the winding of the relay, resulting in the armature 62 thereof moving to circuit closing position, as will be hereinafter described.

The positive line test relay 125 and the negative line test relay 128 are substantial duplicates, each comprising three pairs of contact springs *r*, *b* and *l*, respectively. These three pairs of contact springs are maintained in open circuit condition so long as the relay is energized. Each pair of contacts *r* controls the impressing of positive polarity on the oscillator control bus 65, one contact of each pair being connected with positive battery bus *p* and the other contact being connected with oscillator control bus 65. Each pair of contacts *l* controls the illumination of a trouble lamp which is individual to that relay. For example, one contact *l* of positive line test relay 125 is connected to the feeder or bus 51 of the lamp and trouble bell circuit 51, 52, and the other contact *l* is connected to trouble lamp 131, the other terminal of said trouble lamp being connected to the other feeder or bus 52. The same is true of the negative line test relay 128, its two contacts *l* controlling a similar circuit for a trouble lamp 132 which is individual to this relay. The third pair of bell controlling contacts *b* of each relay controls the energization of the trouble bell bus 51', which extends down for connection with the trouble bell 102, as previously described. The closing of the contacts *b* of either relay 125 or 128 impresses the polarity of bus 51 on the trouble bell bus 51' and causes the trouble bell to ring. It will thus be seen that any break in the continuity of either looped conductor P or N will perform three functions simultaneously through the deenergization of its respective line test relay, to-wit: first, it will impress positive battery 70 polarity through contacts *r* on the oscillator control bus 65; second, it will light the individual trouble lamp 131 or 132, depending upon which relay has been deenergized; and, third, it will apply the polarity of power supply bus 51 to the 75

trouble bell bus 51' for sounding the trouble bell 102. Thus, both box operating conductors P and N are under continuous test for any accidental break in the continuity thereof. As will be hereinafter described, the operation of any one of the signal boxes A, B, C, etc., also interrupts the returns of these two conductors back to their respective line test relays 125 and 128 and thus deenergizes both of said relays, causing both to perform the same three functions enumerated above. At this time, the energization of the oscillator 114 through oscillator control bus 65 starts the transmission of intermittent impulses from that device.

Referring particularly to this oscillator or pulsator, such device functions, when pulsating, to transmit current pulsations to the signaling box then operating and to the recorder; and also to the summary indicator, and to the general alarm bells, depending what classes of signals are being transmitted. This oscillator or pulsator synchronizes the different operations of all apparatus which is brought into operation during a signaling cycle. As previously stated, this oscillator creates current pulsations or variations by the oscillating motion of the mercury tube 116. This is the preferred arrangement although it will be understood that other arrangements of switching contacts may be employed, or other types of devices may be employed for producing current impulses or producing undulating or alternating currents. For example, an alternator may be employed for producing alternating currents, such alternator being of sufficiently low frequency that the signaling boxes, recorder, bells, etc., can keep in step with it. As illustrative of still another arrangement using the oscillator 114, a shunt of relatively high resistance may be connected between the tube terminals 115, 115' so that in the oscillation of the tube, current undulations are produced but there is never a complete interruption of the current flow. Referring again to the arrangement illustrated, since the mercury tube 116 is interposed in series in the negative supply to the two box operating circuit conductors P and N, it follows that when said oscillator is operating it is creating current impulses which are effective at the signaling box over both conductors P and N. Normally, the mercury tube 116 is in its closed circuit position whereby the continuous testing currents are transmitted over both conductors P and N through the mercury immersion of the two terminals 115, 115'. The oscillator comprises a winding or windings 117 adapted, when energized, to attract an armature 118. This armature is mechanically arranged to tilt the mercury tube 72 to open circuit position when the windings 117 are energized. A wire 119 extends from the mercury tube terminal 115' to one end of the winding 117, supplying negative polarity to this end of the winding. The other end of said winding is connected through wire 120 with the oscillator control bus 65. As previously described, the full energization of the full-cycle control relay 58, or the deenergization of either of the positive or negative line test relays 125 and 128 places positive battery potential on the oscillator control bus 65 and thus completes a circuit for the oscillator winding 117 of sufficient current carrying capacity to cause attractive movement of the armature 118. With each upward movement of the armature and consequent tilting of the mercury tube to open circuit position the oscillator interrupts the supply of negative polarity to its own winding 117 through wire 119, and

with each retractive movement of said armature the circuit through said winding is again completed. Hence, so long as positive battery potential is impressed on oscillator control bus 65, the oscillator will continue to operate for transmitting or creating current impulses or current variations effective at the signaling transmitter, the recorder, the summary indicator, etc. The transmission of these negative polarity impulses to the recorder, summary indicator, etc., occurs through negative oscillator bus or feeder 135 which extends down from wire 121.

The oscillator is maintained under continuous test by an oscillator test relay 136, the general function of which is disclosed in my above mentioned patent.

An appropriate condenser 141 may be connected in shunt across the mercury tube terminals 115, 115' for reducing arcing at these terminals. Three surge arresters 142, 143 and 144 are connected in series relation, with this series relation placed in shunt across the mercury tube terminals 115, 115'. A mid-point tap between surge arresters 142 and 143 is connected through wire 145 with positive battery bus p; and a mid-point tap between surge arresters 143 and 144 is connected through wire 146 with ground at 147.

Referring now to the signal loop S which extends in series through the several signal boxes A, B, C, etc., one end of this signal conductor is connected to central station terminal S1, and the other end of said conductor after looping down through the series of boxes is connected to central station terminal S2. A continuous current normally flows through this signaling loop. Referring to the lefthand side of Figure 1B, positive polarity is transmitted from positive battery bus p through wire 149 to the winding or windings 151 of the transfer relay or selecting switch 150. Thus, this righthand end of said relay winding always has positive battery polarity impressed thereon. Under normal, non-signaling conditions negative battery polarity is conducted to the other end of said relay winding through the signaling loop S. This negative polarity is transmitted from the first negative battery bus n through wire 161 to a current protecting resistance 162, and from the other end of this resistance a wire 163 extends to the central station terminal S2. The current path is continued from this terminal through the signaling loop S extending in series through all of the signaling boxes and looping back to the other central station terminal S1. From here a wire 164 extends to the lefthand end of the winding 151 of transfer relay 150. The resistance 162 passes just enough current through the signaling loop to maintain this transfer relay winding continuously energized during non-signaling intervals for holding the movable switching elements of said relay attracted to the full line positions shown. The signaling loop S is maintained continuous at all times, there being no interruption in the continuity of this loop during the signaling operations of any of the boxes. The signaling operations performed by the boxes will be described in detail later but it may be remarked here that such are performed by making and breaking a cross-connection at the signaling box from box operating circuit conductor P to the signaling loop S, i. e., intermittently applying impulses of positive battery polarity to the signaling loop, these impulses being in the code of the signal transmitted by that box. Under normal conditions when no signal box is operating, there is no

cross connection established between the conductor P and the signaling loop S. However, as soon as one of the boxes starts operating, this cross-connection is intermittently established by 5 the operating box for intermittently impressing in coded sequence the positive polarity of conductor P on the lefthand end of transfer relay winding 151 through the signaling loop. Each such positive impulse on the loop deenergizes 10 said winding 151. This is because of the presence of the high resistance 162 in the negative connection to the loop, which means that the negative polarity applied to the loop will be at a lower potential than the positive polarity established 15 through the cross connection at the signaling box. With each interruption of this cross connection the winding 151 is again energized. Thus, the switching elements of the transfer relay are actuated with the making and breaking 20 of this cross connection at the signaling box, whereby the impulses transmitted from the oscillator 114 down through negative oscillator bus 135 are directed either to the step-up coils or to the selector coils of the recorder, as will be 25 presently described.

The continuity of the signaling loop S is maintained under continuous test by a signal circuit test relay 166, which is operable to energize the trouble lamp 169 and trouble bell bus 51', the 30 general operation of this relay being disclosed in my above patent.

Referring now more particularly to the transfer relay 150, the armature of said relay actuates two movable switch elements 153 and 154 which 35 control circuits through three pairs of stationary switch contacts 155, 156 and 157. The negative impulses transmitted from oscillator 114 down through bus 135 are conducted to the step-up and selector coils of the recorder through wires 40 175 and 176. The relay contacts 155 are interposed in wire 175 and the relay contacts 156 are interposed in wire 176. In the normal energized position of the relay armature shown, the circuit down through wire 175 and contacts 155 to the 45 step-up coils is open, and the circuit down through wire 176 and relay contacts 156 to the selector coils is closed. In this condition of the transfer relay the negative impulses transmitted down from the oscillator 114 are transferred or directed 50 towards the selector coils of the recorder. When the winding 151 of the transfer relay is deenergized, a transferring or selecting function is performed by the action of the switch element 153 moving back to the right into engagement with contacts 155, and the action of the 55 switch element 154 moving back out of engagement with the switch contacts 156 and into engagement with the back contacts 157. During this condition of the relay, the negative impulses transmitted down from oscillator 114 are 60 transferred or directed through wire 175 and contacts 155 to the step-up coils of the recorder. The third pair of relay contacts 157 are interposed 65 in a wire 177 which leads from positive battery bus p to one end of the winding of the alarm bell relay 57! which controls the sounding of the general alarm bells 581, 581'. When the transfer relay 150 is energized, the switching element 154 thereof is in a forward position, out 70 of engagement with the contacts 157, at which time no positive battery potential is transmitted over wire 177 to the winding of the alarm bell relay. As above remarked, when the transfer 75 relay is deenergized, the switching element 154

closes the circuit through contacts 157, thereby transmitting positive battery potential through wire 177 to said alarm bell relay. The alarm bell relay is also controlled by the recorder, and a detail description of that relay will be made 5 following the description of the recorder and summary indicator.

From the description thus far, it will be seen that the current for operating the signal boxes or transmitters A, B, C, etc., is conducted to the 10 boxes over conductors P and N; that positive polarity is fed over conductor P in a downward direction through the series of boxes; that negative polarity is fed over conductor N in an upward direction through the series of boxes; and that as soon as any signaling box in the series 15 interrupts the continuity of the return portions of these conductors the oscillator 114 is caused to operate for transmitting intermittent impulses 20 over the line portions of these conductors. With reference to the signaling functions, it will be seen that under normal conditions the transfer relay 150 is energized, but that it is deenergized each time that a signaling box places the positive 25 potential of conductor P on the signaling loop, and that it remains deenergized so long as that positive potential is retained on the loop. It will also be seen that this energization and deenergization of said transfer relay, as controlled by the signaling box, determines whether the impulses from the oscillator transmitted down to the recorder over wires 175 and 176 shall be directed to the step-up coils which advance the printing wheels, or shall be directed towards the 30 selecting coils which select in sequence the printing wheels which are to be advanced.

The transmitters in each of the signal boxes A, B, C, etc., are fundamentally of the same general construction and mode of operation as 40 the transmitters disclosed in my prior Patents Nos. 2,036,330 and 2,164,324, differing from these prior transmitters only in certain improved details of construction and operation. Accordingly, it is not deemed necessary to describe the 45 present transmitters in all detail, since reference may be made to these prior patents for an understanding of the general construction and mode of operation of these electrically driven transmitters. Briefly described, they comprise 50 an advancing coil or coils 209 which are adapted to actuate an armature 214 carrying an advancing pawl 226 which imparts step-by-step advancing movement to the rotor of the transmitter, this advancing movement occurring on the spring 55 retracted movement of the armature after the deenergization of the coil 209. A secondary armature which is also responsive to the coil 209 is arranged to actuate contact 243 out of engagement with contact 242 immediately upon energization of the coil. The secondary armature is of 60 small inertia and has a lead of operation over the main armature 214. The coil is successively energized by the current impulses transmitted over the box operating circuit P, N from the oscillator 114. As the rotor is advanced with a step-by-step rotation, it performs numerous switching functions in a certain sequence or timed relation, and in order to facilitate the understanding 65 of these switching operations the different sets of contact mechanisms or assemblies are arranged in groups in the circuit diagram of Figures 1 and 1A. Six of these contact mechanisms are enclosed in circles, each collectively design- 70 75

5 nated 271, 272, 273, 274, 275 and 276, the circles indicating that the movable or rotor contacts of each particular group advance directly with the advancing motion of the rotor, as indicated by the directional arrows. The ratchet wheel of the rotor functions as a common conducting element for a plurality of the contacts carried by the rotor, and this common conducting function of the ratchet wheel is schematically represented in the circuit diagram by the horizontal conductor designated 228x. The vertical conductors extending down therefrom to the centers of the circles signify that the movable or rotor contacts of that mechanism have common electrical connection with the ratchet wheel.

10 Contact mechanism 271 comprises two diametrically opposite contacts 271a and 271b moving with the rotor and adapted to engage with a 15 stationarily mounted spring pressed contact 271c. The timed relation in this contact mechanism is such that one of the movable contacts engages the stationary contact at a point one step short of the completion of each "round" or half-revolution of the rotor.

15 The function of this contact mechanism is to place a shunt across the secondary armature contacts 242 and 243 at a point one step short of the completion of the round or signaling cycle 20 of the rotor so that the operating box will transmit positive polarity down through conductor P to succeeding boxes lower in the series to allow a subsequently energized box in this direction in the series to take the circuit.

25 Contact mechanism 272 serves to interrupt the transmission of negative polarity up through conductor N to other boxes located above the operating box in the series. This contact mechanism comprises two diametrically opposite moving contacts 272a and 272b, and two stationarily mounted spring pressed contacts 272c and 272d. The first one-step advancement of the rotor shifts the effective contact segment out from under the spring pressed contact 272d, thereby 30 interrupting the transmission of negative polarity up to other boxes further up in the series. When the operating box completes its "round" or signaling cycle, the opposite contact segment moves under the two spring pressed contacts and 35 reestablishes the continuity of the negative conductor N up to the other boxes. The timed relation is such that the first step of advancement opens the negative circuit and the last step of advancement closes the negative circuit.

40 Contact mechanism 273 is concerned with supplying positive polarity to the positive terminal of the transmitter coil 209. Said contact mechanism comprises, in effect, two semi-circular conducting areas 273a and 273b on the ratchet wheel, separated by the two relatively narrow insulating areas 273c. The spring pressed contact 273d is stationarily mounted at a point where the conducting areas 273a, 273b and the insulating areas 273c pass under it. In the normal position of the rotor, this spring pressed contact bears on one of the insulating areas, but in the first step advancement of the rotor one of the conducting areas is moved under it. Said 45 contact is connected with common wire c leading from the energizing switch of the device to which the particular transmitter is to respond, the conductors c, t and o of box A typically representing the circuit connections with such an energizing switch. The contact mechanism 273 insures that

5 once the box has started to signal its signaling cycle, as initiated by this energizing switch, it will continue operating through one round or cycle for completing the signal, even though the energizing switch is not effective to transmit positive polarity to common wire c beyond the first step of the cycle.

10 Contact mechanism 274 comprises a single moving contact 274a having connection with the ratchet wheel, this moving contact being adapted to engage alternatively with two diametrically opposite spring pressed contacts 274b and 274c which are stationarily mounted in the transmitter. Where the box is to respond to a three-wire control, as illustrated by box A, the contact 274b has trouble wire t extending therefrom, and contact 274c has trouble-corrected wire o extending therefrom. In the normal position of the rotor, the movable contact 274a is 15 under one or the other of the two spring pressed contacts. If the box is to respond only to a two-wire control, the wires t and o are multiplied or connected together and extended to the energizing switch as a single wire.

20 The two groups of contact mechanisms 275 and 276 have to do with the application of signaling impulses to the signal conductor S. When the transmitter is to transmit a single type or class of signal, such as watchman's supervisory signals, or emergency fire alarm signals, only the primary signal contact mechanism 275 is utilized. When the transmitter is to have multi-signaling duties for transmitting different types or classes of signals, such as both watchman's supervisory 25 signals and emergency fire alarm signals, the secondary signal contact mechanism 276 is also used in conjunction with the primary signal contact mechanism. The primary signal contact mechanism 275 comprises a series of contacts or 30 conducting areas 275a, 275b, etc., carried by the rotor and receiving positive polarity from the box operating conductor P over connection 228x. As the rotor revolves, said contacts successively move into engagement with a single spring 35 pressed contact 275h which is mounted in the transmitter and which is connected directly with the signaling loop S.

40 The secondary signal contact mechanism 276 comprises one or two signaling contacts 276a and 276aa, disposed on the rotor at a different radius than the primary signaling contacts 275a, 275aa, etc., and receiving positive polarity from the ratchet wheel through the common connection 228x. Cooperating therewith is a single spring 45 pressed contact 276c mounted in the transmitter frame. When this secondary signal contact mechanism is employed in a two-cycle transmitter there are two of these rotor contacts 276a and 276aa located at diametrically opposite points of 50 the rotor; whereas, if this secondary contact mechanism is employed in a single-cycle transmitter, only one of these rotor contacts is provided. In each instance, the secondary contact 276a or 276aa has a lead of operation of one step 55 over the corresponding first contact 275a or 275aa of the primary signal contact mechanism. Hence, it will be seen that whenever the secondary signal contact is rendered operative in a transmitter, its effect is that of lengthening the condition contact 275a or 275aa one step in a forward direction. The control switch mechanism which governs the operation of that particular transmitter determines whether or not the stationary 60

65 70 75 76

contact 275c is connected with the signaling loop S, as clearly illustrated in Figures 1 and 1A.

In some transmitters, a different cyclical operation may be established through the switch mechanism 277 comprising the contact springs 277a, 277b and 277c. The opening and closing of circuits through these contact springs is effected by the cam wheel 262 which is adapted to be advanced by the rotor of the transmitter, and 10 which has varying relations of long and short arms adapted to actuate the contact spring 277a.

Recorder

The improved recorder employed in the system 15 herein disclosed is similar in many respects to the construction of recorder disclosed in my aforementioned prior Patent No. 2,164,324, and attention is directed to that disclosure for some of the more detailed construction. Referring to 20 the improved construction illustrated in present Figures 2 to 9, inclusive, it will be seen that this unit comprises a base casting 308 within which are housed the printing platen, the printing coils for actuating the same, the printing ribbon and 25 its reels, etc. Hinged to the open top of this base casting is a cover 309, on the top of which is secured a housing 311 enclosing the printing wheels, step-up and selector coils, etc., and also secured to this cover is a housing 312 enclosing 30 the time stamp apparatus. Referring to the step-up and selector coils and the printing wheels within the housing 311, it will be observed from Figures 3 and 5, that the step-up coils 313 consist of two coils disposed side by side and secured 35 to the back wall of the housing. The selector or sequence coils 314 also consist of two coils disposed side by side above the step-up coils 313. Responding to the step-up coils is an armature 315 which extends across the core ends of both 40 coils and is pivotally supported at 316 in the side walls of the housing. The armature comprises a forwardly extending plate portion 315' having vertical notches in its front edge, in which notches four advancing pawls 317, 318, 319 and 320 are 45 pivotally mounted on a pivot pin 321. Referring to Figure 3, the pawl 317 operates the condition wheel 322; the pawl 318 operates the hundreds numeral wheel 323; the pawl 319 operates the tens numeral wheel 324; and the pawl 320 operates the units numeral wheel 325. All of these 50 type wheels are coaxially mounted on a common shaft 326 and each type wheel carries a ratchet wheel 327 adapted to be engaged by its individual step-up pawl 317-320.

55 The armature 315 is normally held in its raised position with all four pawls clear of their respective ratchet wheels through the action of two tension springs 329 which have adjustable connection at their upper ends with a stationary cross bar 331 disposed above the armature. The upper limit of movement of the armature is determined by a stop screw 333 having adjustable threaded mounting in the cross bar 331. Secured to the front portion of the armature plate 60 315' is a plate 334 having a down-turned front edge which is adapted to swing down into peripheral notches 335 formed between the type blocks on the printing wheels. This member 334 is adapted to move into one of these notches on 65 the advancing type wheel just at the completion of the down stroke of the advancing pawl, whereby to prevent overthrow of the advancing wheel. Each advancing pawl is formed with two arms, one extending rearwardly and one extending upwardly, i. e., the pawl 317 has an upwardly ex-

tending arm 317' and a rearwardly extending arm 317''; the pawl 318 has an upwardly extending arm 318' and a rearwardly extending arm 318'', etc. These arms extend through slots in the plate portion 315' of the armature and through slots in the detent plate 334; and connected to each rearwardly extending arm 317'', 318'', etc., of each pawl is a tension spring 337 having fixed attachment at its rear end to the plate portion 315' of the armature, each of these 10 springs normally tending to swing the lower nose of its associated pawl forwardly into a position to engage the ratchet teeth 327 of its respective type wheel. Whether the pawl is allowed to engage the teeth on its downstroke is determined 15 by the angular position in a transverse shaft 338 which is arranged to coact with the upwardly extending arms or fingers 317', 318', 319', etc., of each advancing pawl. Immediately in rear of each upper pawl finger this shaft 338 is 20 notched out on opposite sides, thereby forming diametrically opposite wing portions 339 which control the operativeness of the pawl. When these wing portions extend in substantially vertical parallelism with the rear edge of the pawl 25 finger 317', 318', etc., the lower nose portion of the pawl is allowed to assume an operative position with respect to its own ratchet wheel, but when the shaft 338 is rotated slightly to swing one of the wing portions 339 forwardly against 30 the pawl finger 317', 318', etc., the pawl is oscillated against the tension of the spring 337 to a position where it is incapable of engaging its ratchet wheel on the downward stroke of the armature. As successive angular movements are 35 imparted to the shaft 338 in this same direction, the pawl will still be held at its inoperative angle with respect to the armature plate 315' until the shaft 338 has been advanced through a half revolution, which again brings the wing portions 40 339 parallel with the pawl finger, allowing the pawl to resume an operative position with respect to the armature. The wing portions 339 cooperating with the pawl for the condition wheel 322 are at a slightly different angle than 45 the wing portions cooperating with the pawl associated with the hundreds wheel, and this applies to the wing portions associated with the other pawls. In the preferred construction the condition wheel 322 is set up first and the 50 numerical wheels are set up in sequence thereafter, and in such arrangement the condition wheel pawl 317 is normally in operative position at the start of the cycle and the other pawls are in inoperative positions at this time. Should it be 55 desired to have the condition wheel set up last or in any other sequence with respect to the other type wheels, the pawls will be given a different timed relation by appropriately changing the relative angles between the wing portions 60 339. Assuming, as before stated, that the condition wheel is the one to be set up first, after this wheel has completed its advancement through the number of steps determined by the particular transmitter which is then signaling, 65 the shaft 338 is caused to rotate in a counter-clockwise direction through the actuation of the selector armature and its associated parts, to be later described. This angular motion of the shaft 338 renders the condition wheel pawl 317 70 inoperative and renders the hundreds wheel pawl 318 operative. Thereupon, the step-up armature 315 is again actuated one or more times to impart step-by-step advancement to the hundreds wheel, assuming that the signal from the 75

transmitter then operating is coded for the advancement of the hundreds wheel. Following this, the shaft 338 is again advanced in the same direction as before, at which time the hundreds wheel pawl is rendered inoperative and the tens wheel pawl is rendered operative. This same procedure follows in transferring impulses to the units wheel 325. It will thus be seen that the shaft 338 functions as a selector element which, 10 by its angular position, determines which pawl is operative and the order in which these pawls are made operative. Motion is imparted to this shaft upon the energization of the selector coils 314 through mechanism hereinafter referred to.

15 Cooperating with the ratchets 327 of the four type wheels are four similar checks or holding pawls 341 which are pivotally mounted at 342 in slots formed in a transverse mounting bar or block 343. The nose of each holding pawl is 20 adapted to swing down into the ratchet teeth of its associated type wheel to hold the type wheel after each step-by-step advancement. A tail 344 on each holding pawl bears against the top of a compression spring 345 (Figure 5) seated in a 25 cylindrical pocket in the mounting block 343, this spring normally tending to swing the nose of the pawl down into the ratchet teeth. At the conclusion of a printing operation all four holding pawls are simultaneously swung up to releasing position out of the ratchet teeth through the oscillation of a transverse shaft 346, which is journaled in the block 343. Milled in said shaft are flat faces 347 which cooperate with shoulders 348 on the holding pawls. When these 30 flat faces are substantially parallel with the shoulders 348, the pawls are permitted to swing down into the teeth of their respective ratchets under the action of the springs 345, but when the shaft 346 is rotated counterclockwise to bring rounded portions of the shaft against the shoulders 348, all four pawls are swung upward to releasing positions. When this occurs at the 35 end of a printing operation, such type wheels as have been advanced are immediately restored to their original positions by the action of spiral springs 351 associated with each type wheel. Referring to Figure 7, one of these springs is enclosed within a drum or spring housing 352 at the end of each type wheel, the inner end of the spring being secured to the shaft 326 and the outer end being secured to the housing. The 40 springs all tend to rotate the advanced type wheels in a clockwise direction back to their original positions, which original positions are determined by radially projecting shoulders 353 on the spring housings striking stop fingers 354 which extend from a cross bar 355 down into the paths of these shoulders.

45 As shown in Figures 2 and 3, a vertical partition plate 356 is disposed immediately to the left of the series of type wheels, and arranged in the space between this partition plate and the left-hand wall of the housing are certain operating mechanisms and contact devices which I shall now describe. Referring to Figure 6, a pivot stud 357 anchored to this partition plate 356 has rockably mounted thereon a tripping pawl 358 which is adapted to release the shaft 346 which allows the holding pawls 341 to engage the ratchets 327.

50 A laterally bent end 359 on this tripping pawl 358 projects backwardly through a hole 361 in the partition plate into a position lying in the path of the armature plate portion 315' so that when the step-up coils 313 are first energized at 55 the beginning of a recording cycle, the initial

downward movement of the armature plate portion 315' strikes this tail projection 359 and oscillates the tripping pawl 358. The other end of said pawl is formed with a hook 362 which is adapted to engage with a shoulder 363 formed in 5 a notched hub or collar 364 secured to the shaft 346. A tension spring 367 normally holds the hook end of said pawl in engagement with the shoulder 363. The rocking movement of the tripping pawl 358, consequent upon the first energization of the step-up coils, swings the hook 362 out of engagement with the shoulder 363. Upon this release of the notched collar 364, a tension spring 365 operatively connected to said collar, quickly oscillates the collar and shaft in the clockwise 10 direction for turning the flat faces 347 into registry with the shoulders 348 to permit the holding pawls 341 to swing down into operative engagement with their respective ratchet wheels 327. The collar 364 is provided with an arm 366 extending down into the base casting 308 where it is arranged to be restored in a counterclockwise direction (as viewed in Figure 4) through the actuation of mechanism which is responsive to the return movement of the printing platen. 15 This operation, occurring after the completion of the recording cycle, oscillates the shaft 346 in a counterclockwise direction for swinging all of the holding pawls 341 up to their released position and locking them in these positions, as will appear from the later description of the printing platen, etc.

20 Summarizing the recorder mechanism described thus far, the first actuation of the step-up armature 315 operates through the advancing pawl 317 to advance the condition wheel 322 one step; this wheel is retained in that position by its individual holding pawl 341, all of which holding pawls have been dropped to operative position in the downstroke of the armature plate portion 315' before the operative advancing pawl 317 starts to move back in its retractive movement and before the spring 351 can start to rotate this condition wheel backwardly. Thus, both operations of advancing the condition wheel and tripping the holding pawls to hold this and the other wheels, occur on the first current impulse transmitted to the step-up coils 313. Thereafter, each succeeding one step advancement imparted to the type wheels is retained by the holding pawls 341, 25 until the completion of the printing operation. As above remarked, the return motion of the platen after the printing operation functions through intermediate mechanism to oscillate the arm 366 and rock the shaft 346 in a return or counterclockwise direction, allowing the hook 362 of the tripping pawl 358 to swing down into engagement with the shoulder 363, and concurrent therewith swinging all of the holding pawls 341 up to their released positions and locking them in these positions, until the next oscillation of the step-up armature 315 at the beginning of another recording operation, whereupon the pawl or lever 358 is again tripped and all of the holding pawls are again allowed to swing down to their operative 30 position, as previously described.

30 Referring now to the mechanism by which the energization of the selector coils 314 imparts advancing movement to the selector shaft 338, it will be observed from Figures 5 and 6 that the 35 magnet cores of these two coils attract an armature 371 which is pivotally mounted at its upper edge at 372. A pin 373 projects laterally from the lower edge of the armature and extends out through an opening 374 in the partition plate 375

356. Here this pin is pivotally connected to a link 375 which is pivotally connected at 376 to the upper arm of a lever 377. Said lever is pivotally supported on a stud 378 projecting outwardly from the side of the partition plate 356, and also mounted on this stud, but rotatable independently of the lever 377, is a ratchet wheel 379 and a spur gear 381 which are both joined together or integral for concurrent movement. Pivotally mounted at 382 on the upper arm of the lever is a pawl 383, having a hook-shaped nose adapted to impart clockwise advancement to the ratchet wheel 379 when the lever 377 is oscillated clockwise. A coiled spring 384 connected between the lever 377 and the forwardly extending arm of the pawl 383 functions to hold the hook end of the pawl in engagement with the ratchet teeth. A relatively heavy tension spring 385 is connected between the lower arm of the lever 377 and a fixed point of attachment on the housing structure, such spring tending to oscillate the lever in a clockwise direction. A detent pawl 386, pivotally mounted at 387 and having a tension spring 388 connected thereto, is arranged to engage in the teeth of the ratchet wheel 379 to prevent retrograde movement of the latter in the oscillation of the lever 377. The spur gear 381 meshes with a spur pinion 389 which is secured to the selector shaft 338, the pinion being one-half the diameter of the spur gear 381.

It will be evident that when the selector coils 314 are energized, the movement of the armature 371 will operate through the link 375 to oscillate the lever 377 and pawl 383 in a counterclockwise direction, the pawl merely slipping idly over the next ratchet tooth in this movement occurring during the energization of the selector coils. When the selector coils are deenergized, however, the spring 385 quickly oscillates the lever 377 in a clockwise direction and in such movement the pawl 383 advances the ratchet wheel 379 and spur gear 381 through a distance equal to one ratchet tooth. Any suitable stop means may be provided for determining both limits of throw of the lever 377 so that such movement always results in a one tooth advancement of the ratchet wheel. In the construction illustrated, a stop function is performed by having the forwardly extending tail end of the pawl 383 engage a stationary stud or shoulder 390 carried by the housing. As the spur gear 381 is advanced in a clockwise direction, the selector shaft 338 is advanced in a counterclockwise direction, this shaft making one complete revolution for each half revolution of the spur gear 381. The shaft 338 is advanced through only one-half revolution during each recording cycle, it being evident that a half revolution again places the wing portions 339 of said shaft in their same general relation to the upwardly extending fingers 317, 318', etc., of the several advancing pawls.

Mounted on the end of the selector shaft 338 are the rotating contact elements of three rotary switches 401, 402 and 403. Cooperating with these rotating contact elements are pairs of spring contacts 401a, 402a and 403a which bear against the rotary members at diametrically opposite sides thereof. The rotating contacts are mounted in a hub or cylinder 404 composed of insulating material and secured fast to the shaft 338. The switch mechanisms 401 and 402 each have a metallic pin or rod 401b, 402b extending diametrically through the insulating hub 404, the ends of these conducting pins or rods being exposed at the peripheral surface of the drum for

establishing cross connection between their associated contact springs 401a-401a and 402a-402a once in each half revolution of the rotary switches. The rotary switch 403 comprises a metallic conducting member 403b of approximately H-shape with relatively long arcuate conducting areas and with relatively narrow recesses at diametrically opposite points, as best shown in Figure 6. This conducting member is recessed into the end of the insulating hub 404 and is secured thereto by screws 405. Portions of insulating material 403c extending into the diametrically opposite recesses of the conducting element 403b establish insulating areas on the periphery of the rotary switch for opening the circuit between the contact springs 403a. In the normal condition of the recorder, the transverse conducting pins 401b, 402b of the two switches 401 and 402 both occupy positions one step in advance of their circuit closing positions; and at this time the insulating segments 403c, 403c are disposed directly under the spring contacts 403a, 403a in circuit opening position. A complete recording cycle rotates the three switches through 180°, bringing the conducting pins and the insulating segments back into the positions illustrated, except that the pins and segments are turned end for end, or reversed. The lower ends of the three sets of contact springs are secured to an insulating block 406, and from these contact springs 30 wires extend to the selector coils, the printing coils, the alarm bell relay, etc., as will be later described.

Contact mechanism 411 is also associated with the tripping shaft 346 which trips the holding pawls 341 into and out of operative positions. This mechanism comprises two spaced contact springs 411a, 411a which extend forwardly above the shaft 346. A contact collar 411b is adapted to oscillate with the motion of said shaft into 40 and out of circuit closing position between the contact springs 411a. This contact collar 411b is secured to an insulating post 412 which extends upwardly from a collar 413 secured to the shaft 346. The rear ends of the spaced contact 45 springs 411a are secured to an insulating mounting block 414. In the normal condition of the recorder the conducting collar 411b lies in open circuit position out of engagement with the contact springs 411a, but as soon as the tripping pawl 358 is actuated on the initial energization of the step-up coils 313 the resulting tripping movement of the shaft 346 swings the conducting collar 411b forwardly into a position where it completes a circuit between the two contact springs 55 411a, 411a. This contact mechanism 411 controls the supply of positive battery polarity to the selector coils 314, as will be later described.

Responsive to the motion of the condition wheel 322 is a selector switch mechanism 416 60 which controls the energization of the alarm bell relay and which also determines whether the summary indicator is to be actuated and whether an adding or subtracting operation is to be performed at the summary indicator. This 65 selector switch comprises a rotating switch arm 416' which is adapted to engage successively with stationary switch contacts 416a, 416b, 416c, etc., arranged circularly in an insulating disc or mounting member 417. Referring to Figure 8, 70 the rotating switch arm 416' comprises a contact spring which has one end secured by screws or rivets 418 to a mounting disc 419 composed of insulating material. This mounting disc and the rotating switch arm are advanced in direct 75

step with the successive advancing movements imparted to the condition wheel 322 through suitable gear mechanism comprising a large spur gear 422 (Figure 5) secured directly to the adjacent end of the condition wheel and meshing with a pinion 423. This pinion is secured to a short countershaft 424 which is journaled in the partition wall 356. The other end of said countershaft carries a similar spur pinion 425 which meshes with a corresponding spur gear 426 secured to the mounting disc 419. Said mounting disc 419 and gear 426 are rotatably mounted on any appropriate pivot support, such as on the end of the pivot stud 367 which carries the tripping pawl 358. A circuit connection is established with the switch arm 416' through a spring contact 427 which bears against the switch arm at its center of rotation. There are preferably as many of the circularly arranged contacts 416a, 416b, etc., as there are printing faces on the condition type wheel 322. The face of the condition wheel which is normally in printing position is preferably a blank face, and the normal position of the switch arm 416', corresponding to this position of the condition wheel, is preferably a blank position, in that the switch arm is not then engaging any stationary contact which is electrically effective. As the condition wheel is advanced for presenting the first type face and then succeeding type faces to printing position, the switch arm 416' is correspondingly advanced to engage with the first effective contact 416a and then with succeeding contacts 416b, 416c, etc. The circuit connections between the latter contacts and the alarm bell relay and summary indicator will be later described.

Referring now to the printing coils, platen, and other mechanism within the base casting 308, it will be seen from Figure 2 that the front of this casting is formed with a relatively wide central compartment 434 in the approximate center thereof, down through which travels the paper tape 435 (Figures 4 and 9) upon which the records are printed. The sides of this central compartment are defined by vertical partition walls 436, 436, only the lefthand one of which appears in Figure 2. Defined between these partition walls and the outer side walls 437 of the base casting are right and lefthand compartments 438, 438, the lefthand one of which appears in Figure 2. Vertically disposed in this lefthand compartment are the two printing coils 441 which attract an armature 442 extending across the tops of the coils. As best shown in Figure 4, it is the rear end of this armature that swings down towards the coils, the armature being mounted on a pivot shaft 443 which is located forwardly of the core ends of the coils and which shaft is carried by suitable trunnions supported by the side walls of the compartment 438. The armature is formed with an arm 442' extending forwardly of the pivot axis 443 for connection with a tension spring 446 which is suitably anchored at its lower end to the base casting, this spring normally tending to swing the armature upwardly away from the core ends of the printing coils. Projecting laterally inwardly from the swinging end of the armature is a pin 447 which projects into the central compartment 434 through a vertical slot 448 (Figure 4) in the upper portion of the partition wall 436. The end of this pin has reception in a hole in a motion transmitting lever 449, which hole is enlarged laterally to accommodate slight sidewise

movement of the pin therein. The rear end of the motion transmitting lever 449 is pivotally mounted on a stud 451 projecting inwardly from the partition wall 436. The front end of said lever has a long slot 452 therein, in which operates a pin 453 carried by one arm of a bell crank lever 454, the latter lever comprising a downwardly extending arm 454' adapted to carry one end of the printing platen. This bell crank lever is freely oscillatable on a shaft 455 on which are mounted the paper feeding rolls 456 and 457. The ends of the shaft 455 are journaled in the partition walls 436 at opposite sides of the central compartment 434. At the right side of the central compartment 434 is an arm 458 (see Figure 9) which is similar to the lower arm 454' of the bell crank lever 454, and which is also freely oscillatable on the shaft 455. Extending between the extremities of these arms is a tie rod 459 and extending between the middle portions of said arms is a channel-shaped platen supporting bar 461 in which the rubber platen block 462 is mounted. From the description thus far, it will be seen that the downstroke of the armature 442 upon the energization of the printing coils 441 will oscillate the motion transmitting lever 449 downwardly, which in turn will swing the two arms 454' and 458 in an upward direction, carrying the platen 462 up into printing position. This printing position is defined by an inked ribbon 463 which extends transversely across the upper portion of the base casting directly below the printing faces of the type wheels. The paper tape 435 extends from the supply roll 435' across the tops of the feeding rolls 456, 457 and across the top of the platen 462 so that in the upward movement of the platen this paper tape is swung up against the bottom of the inked ribbon 463, through which it receives its printed impressions from the type wheels. The upward movement of the arms 454', 458 does not rotate the shaft 455, but the downward movement, after a printing operation, is arranged to advance this shaft for turning the feeding rolls the required distance for advancing the paper tape. Referring to Figure 9, the arm 458 carries a spring pressed pawl 465 which engages and rotates a ratchet wheel 466 when the arm swings downwardly, this ratchet wheel being secured to the shaft 455. A suitable spring pressed detent pawl 467 prevents reverse rotation of the ratchet wheel when the platen swings upwardly. The forward rotation of said shaft rotates the feeding rolls 456, 457 and advances the paper tape the required distance for its next printing impression, the central roll 457 consisting either of a rubber wheel or a knurled steel wheel which presses firmly against the paper tape, reacting against a small roller 469 rotatably supported on a shaft 471 (Figure 4) which is secured to the hinged cover 309.

The mechanism for actuating the restoring arm 366 and thereby restoring the holding pawls 341 to normal position and restoring the contact mechanism 411 to open circuit condition, comprises a rock shaft 473 (Figures 2 and 4) which is journaled in the walls 436 and 437 of the lefthand compartment 438. The inner end of this shaft projects beyond the wall 436 into the central compartment 434, and secured to this end of said shaft is a lever 474 (Figure 2). Also secured to this shaft, within the end compartment 438, is a lever 477 comprising upper and lower arms 477a and 477b. Attached to the lower arm of said latter lever is a tension spring 481, which

has its lower end suitably attached to the base structure. The spring 481 exerts a constant biasing action on the shaft, tending to hold the upper arm 471a of the lever 471 upright, and tending 5 to hold the other lever 474 in a substantially horizontal position, see Figure 4. The restoring arm 366 extends down from the tripping shaft 346 into the base casting to a position immediately in front of the upper lever arm 471a, 10 whereby when this latter lever arm is rocked forwardly it engages and forces the restoring arm 366 forwardly for releasing the holding pawls and for swinging the movable contact 411b of the contact mechanism 411 back into 15 its normal, open circuit position. The lever arm 474 has a beveled end 474' with which a stud 459' on the bell crank lever arm 454' cooperates. As shown in Figure 2, this stud may consist of a reduced end of the tie rod 459, protruding beyond 20 the bell crank lever. On the upward movement of the platen the stud 459' engages the lower edge of the arm 474 and starts to swing the latter upwardly, but because of the eccentricity between the centers of the shafts 455 and 473, 25 this stud soon slips past the beveled end 474' and continues its upward movement above the lever arm 474. On the downswing of the platen the stud 459' engages the upper side of the lever 474 and swings the latter downwardly to approximately 30 the dotted line position indicated at x in Figure 4, at which point the arc of the beveled tip 474' swings inside of the arc of the stud 459' so that the stud is allowed to continue its movement past the end of the arm 474. Instantly, the 35 lever 474 is restored to its normal position under the biasing action of the spring 481. In such downward swinging movement, however, the lever 474 also rocks the upper arm 471a of the lever 471 in a forward direction, and this movement 40 operates to thrust the restoring arm 366 from the dotted line position to the full line position shown in Figure 4, thereby releasing the type wheels and restoring the contact mechanism 411 to open circuit condition, all at the completion of the printing operation when the platen is swinging downwardly to its normal position.

As the paper tape travels downwardly from its printing position, it is fed into a lower box which is normally locked against unauthorized access, 50 in order to prevent any attempt to alter the records on the tape. A glass cover may be arranged to close the front of the central compartment 434, if desired. Mounted at any suitable point within or adjacent to the central compartment 434 is a lamp 485 (Figure 2) which is adapted to illuminate the paper tape. Said lamp is automatically lighted at the start of any signaling cycle and remains lighted until the system 55 is reset to normal, the energization of said lamp being under the control of the reset relay which will be later described.

The electrically operated time stamp 312 is of any conventional type comprising printing time wheels which are advanced periodically, such as 60 each minute, from electrical impulses transmitted from a master clock, or through the instrumentality of a synchronous motor connected with the power supply circuit 51, 52 in installations where this circuit receives alternating current of regulated frequency. These time wheels print on the paper tape, alongside the condition and numeral wheels, the day, month and year and time of day when each signal is received and recorded. Included in or associated with the recorder are 65 numerous other mechanisms which are fully dis-

closed in my prior Patent No. 2,164,324, and to which attention is directed for the details thereof. Such mechanisms include improved means for supporting the paper supply roll 435' whereby a new roll may be readily substituted for a depleted roll; improved mechanism responsive to the amount of paper on the supply roll for giving a lower paper indication when a new roll should be substituted; improved mechanism for feeding the inked ribbon 463 from one reel to the other and for intermittently reversing the drive to these reels; and improved circuit opening means for opening the main battery circuit and opening the various circuits leading to the instrumentalities of the recorder as soon as the hinged 10 cover 309 is swung back in the act of gaining access to the base casting for changing the paper supply rolls, inked ribbon reels, etc., the opening of said circuits preventing the operation of the system so long as the recorder is incapable of 15 performing a recording operation. The arrangement is preferably such that the opening of the hinged cover 309 first requires the release of the key controlled lock, so that unauthorized persons cannot interrupt the normal operation of the 20 system.

The summary indicator (Figure 1C) which responds to the selector switch mechanism 416, comprises a numbered disk (not shown) which is rotated step by step in a forward or additive 25 direction by successive energizations of the add coil 517, and which is rotated step by step in a rearward or subtractive direction by successive energizations of the subtract coil 518. The successive numbers in this disk are illuminated by 30 the bulb 509 as they are presented to view in a sight window of the summary indicator. A cam 541 which rotates with the numbered disk operates through a cam follower lever 542 to control the contact apparatus 546, 547, and 548. The 35 arrangement is such that when the disk is in its normal position with the "0" thereof exposed in the sight window, the follower lever 542 is engaging in the notch in the cam 541, with the result that the contacts 546—547 are engaged, 40 thereby energizing a bulb 553 which gives a green or "OK" indication in the summary indicator. As soon as the indicating disk is advanced one or more steps from its zero position, the lever 542 is forced out of the recess in the cam, and thereafter rides on the circular periphery of the cam, 45 the resulting rocking motion of the lever pressing the intermediate contact spring 546 downwardly out of engagement with the upper contact spring 547 and into engagement with the lower contact spring 548. Such deenergizes the bulb 553, and energizes another bulb 554 which gives a red or trouble indication in the summary indicator. The latter relation of the lever 542 and of the contact springs will be maintained as 50 long as any numeral on the disk appears at the sight window, but when the indicating disk is restored to its "0" position, the lever will be restored to its normal position, at which time the intermediate contact spring will move out of 55 engagement with the lower contact spring 548 and into engagement with the upper contact spring 547, thereby extinguishing the red bulb 554 and illuminating the green bulb 553. It will thus be seen that the summary indicator gives an 60 instantaneous visual indication of the supervisory condition of the system. For example, as supervisory signals are transmitted to central station for indicating different conditions which may be 65 actual or potential sources of trouble, such as 70 75

- the manual closing of a critical control valve, the loss of adequate pressure on the water supply system, etc., these trouble conditions are automatically totalized on the summary indicator.
- 5 As the engineer or other attendants proceed with the correction of these conditions at different points in the plant, the number of conditions are automatically subtracted from the totalized indication of the summary indicator. Thus, the summary indicator gives an instantaneous visual indication as to whether or not any trouble condition exists in the installation, and the total number of such trouble conditions which have not been attended to. In this manner, the summary indicator checks the human element in the observation of the trouble conditions recorded at the recorder. For instance, if the recorder indicates that five trouble conditions have developed at different points in the installation, and the attendants correct only four of these, overlooking the fifth trouble condition, the summary indicator will still indicate that one trouble condition remains which has not received attention.
- 10 Referring now to Figures 1B and 1C, and particularly to the circuit connections between the transfer relay 150, the recorder, the summary indicator, and the alarm bell relay, it will be recalled that negative impulses are transmitted from the oscillator 114 through bus 135 and wire 175 to the step-up coils 313 of the recorder whenever the transfer relay 150 is deenergized during a signaling operation, such deenergization causing the movable switch element 153 to engage with the switch contacts 155 and complete the circuit through wire 175. The opposite terminal of the step-up coils 313 has positive polarity continuously impressed thereupon through wire 561 which leads from the positive battery bus p to these coils, whereby said coils will be energized each time that they receive a negative impulse down through wire 175. During the normal, non-signaling condition of the system, the selector coils 314 do not have positive polarity impressed thereon. A branch wire 561' extends from the wire 561 to the selector coils, but interposed in this wire is the contact mechanism 411, which contact mechanism is responsive to the position of the tripping shaft 346 in the recorder, as previously described. As soon as the step-up coils 313 have been energized once in the start of a signaling cycle, the consequent actuation of the tripping pawl 358 and release of the tripping shaft 346 causes the contact mechanism 411 to move to closed circuit position, after which positive polarity is transmitted to the selector coils through wire 561' and contact mechanism 411 during the remainder of the signaling cycle, or until the actuation of the printing platen has caused the tripping shaft 346 to be restored to its normal position and the contact mechanism 411 restored to open circuit position. So long as the selector coils receive positive polarity through contact mechanism 411, they will be energized each time that a negative impulse is transmitted from oscillator 114 down through wire 176 and contact mechanism 154, 156 to the other terminal of the coils. Thus, during the signaling cycle, each time that a negative impulse is transmitted down from the oscillator during any interval that the transfer relay 150 is energized, holding the movable switch element 154 in engagement with the switch contacts 156, this negative impulse, or impulses will energize the selector coils. At a point one step short of the completion of the recording cycle, the selector coils will also be

energized through the rotary switch contact mechanism 401. This contact mechanism is interposed in a wire 562 which extends from the negative oscillator bus 135 to the negative terminal of the selector coils. As previously described, the rotary contact mechanism 401 arrives in closed circuit position at a point one step short of the completion of the recording cycle and, hence, at this time the selector coils will be energized irrespective of whether the transfer relay 150 is energized or deenergized. Such final energization of the selector coils restores the selector mechanism to its original condition, which also restores the three rotary switches 401, 402 and 403 to their original open circuit positions.

15 At the same time that the rotary switch 401 is transmitting the final negative impulse of the cycle to the selector coils 314, the second rotary switch 402 is transmitting positive battery potential to the positive terminal of the printing coils 441. The latter switch is interposed in a wire 564 extending from the positive battery bus p to the printing coils. A wire 565 connects the other terminal of said coils to the negative oscillator bus 135. As previously described, the advancing motion of the three rotary switches 401, 402 and 403 occurs upon the deenergization of the selector coils, and when the two switches 401 and 402 arrive in their closed circuit positions (one step short of the completion of the recorder cycle), the next negative impulse transmitted from the oscillator 114 down through bus 135 simultaneously energizes the selector coils 314 and the printing coils 441, the latter causing the printing operation. The subsequent deenergization of the selector coils 314, at the end of the negative impulse transmitted down from the oscillator, advances the three rotary switches one more step to their normal or open circuit positions, and at this time the controlling switch 411 for the positive polarity end of the selector coils is also restored to its open circuit condition.

20 Referring now to the rotary switch 403 and the selector switch 416, attention is first particularly directed to the fact that the printing coils 441 are wound for a relatively heavy current flow, the relation between these coils and the associated printing mechanism being such that a relatively large current flow is required through 25 the coils to effect the printing operation. Hence, during all of the early steps of the recording cycle, relatively small currents can be conducted through these printing coils to the selector switch 416 without causing actuation of the 30 printing mechanism. Such small currents are conducted from what would be regarded as the positive terminal of these coils through wire 427' and contact clip 427 to the rotating switch arm 416' of the selector switch. That is to say, during all of the steps of the recording cycle, except at the time that the printing coils are fully energized for a printing operation, the impulses transmitted from the oscillator 114 down through negative oscillator bus 135 are conducted through 35 wire 565, printing coils 441 and wire 427' and clip 427 to the switch arm 416', these impulses being conveniently regarded as of negative potential. However, at that time when the rotary switch 402 arrives in closed circuit position and 40 transmits positive polarity through wire 564 to the positive terminal of the printing coils this positive potential is also transmitted through wire 427' and clip 427 to the selector switch arm 416'. Referring first to the manner in which 45

the negative impulses effective on the switch arm are transmitted to the alarm bell relay in the event of a fire signal, when the switch arm 416' is in its normal position, illustrated in full lines 5 in the drawings, it is not engaging any active stationary contact on the face of the selector switch, this normal position of the switch arm corresponding to a blank face on the condition wheel 322, which blank face is presented in the 10 printing position during the normal condition of the recorder. The first impulse transmitted to the recorder during a recording cycle energizes the step-up coils 313, as has been previously described, and this impulse advances the condition wheel one step. Such brings the switch arm 15 416' into engagement with the first effective stationary contact 416a. In a system having fire alarm signaling as one of its functions, the preferred grouping of the signals on the condition wheel 322 is such that the first type face following the blank type face shall print "Fire"; although it will be understood that watchmen's call signals, operator's acknowledgement signals, or any other desired signals, may precede the 20 "Fire" signal on the successive type faces of the condition wheel. Assuming, however, that the contact 416a corresponds to a fire signaling position of the condition wheel and that a fire signal is being transmitted, the condition wheel and 25 switch arm will only be advanced through this one step before the selector coils are energized for having succeeding "numeral" impulses effective to advance the numeral wheels. Hence, the condition wheel and switch arm will remain 30 in this position during the rest of the signaling cycle while the remaining impulses are being utilized to advance the numeral wheels. These remaining impulses, designating the number of the particular box then signaling, will be transmitted 35 through switch arm 416', contact 416a, and wire 568 to one terminal of the rotary switch 403. Said rotary switch was advanced one step to its circuit closing position upon the deenergization of the selector coils 314, which deenergization 40 has operated through the selector mechanism to have these succeeding "numeral" impulses effective to advance the numeral wheels. A wire 569 extends from the other spring contact of the rotary switch 403 to one end of the 45 winding 572 of the alarm bell relay 571, whereby these "numeral" impulses of a fire signal are transmitted to the relay winding 572. The other end of said relay winding receives positive battery potential through wire 177 which extends 50 from positive battery bus p through the back contacts 157 of the transfer relay 150. During the intervals that said transfer relay 150 is deenergized for directing negative impulses through back contacts 155 to the step-up coils 55 as numeral impulses, the deenergized condition of said relay is also closing the circuit through the other pair of back contacts 157 so that the positive end of the alarm bell relay winding is receiving positive polarity through wire 177. Hence, the alarm bell relay is energized in succession by each negative impulse transmitted to the opposite end of its winding through selector switch 416 and rotary switch 403. Said alarm bell relay comprises two movable switch elements 60 573 and 574 which respond to each energization of the winding 572, both switch elements moving into engagement with their respective front contacts 573' and 574'. Current from the positive battery bus P is conducted through wire 575 to one switch element 573, and current from the

second negative battery bus n' is conducted through wire 576 to the other switch element 574. Connected in parallel across the two stationary contacts 573' and 574' is a loop 577 which includes a plurality of general alarm bells 581, 5 the latter being connected in series in said loop. Also extending from the stationary contact 574' is another bell circuit consisting of a conductor 579 extending in series through another group of general alarm bells 581', and connected at its 10 other end to the positive battery bus P.

Thus, it will be seen that each time that the winding of the alarm bell relay is energized by the transmission of the numeral impulses thereto, the closing of the circuits through the relay 15 armatures 573 and 574 will sound the alarm bells 581, 581' concurrently with the numeral impulses. For example, if a box is signaling "Fire 321," the impulse or impulses which designate the "Fire" condition will not be sounded, but as 20 soon as the numeral impulses are transmitted these general alarm bells will first sound three strokes, then two strokes, and then one stroke for identifying the particular box "321" which is transmitting the fire signal. The fact that these 25 general alarm bells are sounding of itself indicates "Fire" or a condition of primary emergency at the location of the box.

Provision is made for manually sounding the general alarm bells 581, 581' from central station 30 at any time that the operator should desire to sound a general alarm. To this end, a double pole, single throw switch 585 is connected through wires 586 and 587 with the positive battery bus p and with the second negative battery bus n'. 35 From the two stationary contacts of this switch extension wires 586' and 587' lead to the positive and negative ends, respectively, of the relay winding 572. Accordingly, the operator at central station, by merely moving the switch 585 to closed 40 circuit position, can energize the alarm bell relay 571 and cause the alarm bells 581, 581' to sound, independently of the operation of the entire signaling system. It will be noted that the wire 576 which supplies negative polarity through relay switch element 574 to the alarm bells draws its 45 negative potential from the second negative battery bus n'; also that the wire 587 which supplies negative polarity through double pole switch 585 to the relay winding 572 likewise draws its 50 negative potential from this second negative battery bus n'. This arrangement is preferred because then the energization of the alarm bells 581, 581' does not in and of itself energize the full-cycle control relay 58. If desired, however, 55 these wires 576 and 587 can be connected to the first negative battery bus n, so that each and every operation of the alarm bells, no matter how originated, will energize the full-cycle control relay.

The alarm bell circuit is maintained under continuous test by a bell circuit test relay 591. A wire 593, extending from one end of the test relay winding 592, is connected through wire 576 with the second negative battery bus n', whereby 60 negative battery polarity is always effective on one end of the relay winding. Extending from the other end of the test relay winding is a wire 594, which connects with the bell circuit loop 577 at a point between the last bell 581 and the 65 associated relay contact 573'. It will be observed that this point of connection supplies positive battery potential to the test relay winding 572 through a series circuit which includes all 70 of the alarm bells 581, 581' and all, or the major 75

portions, of both alarm bell circuits 577 and 579. That is to say, positive battery potential normally flows from bus P through bell circuit 579 and through all of the bells 581' included therein, 5 thence through bell circuit 577 and through all of the bells 581 included therein, and thence through wire 594 to the test relay winding 592. This normal testing current is not sufficiently strong to energize any of the alarm bells. The 10 test relay 591 is normally energized, and in this condition its two pairs of contact springs b and l are maintained in open circuit relation. Any break in the continuity of the alarm bell circuits 577 and 579 or in the circuits of their respective 15 bells deenergizes the test relay 591, which causes said contact springs b and l to move to closed circuit relation. The contacts l complete a circuit for an individual trouble lamp 595 and the contacts b complete a circuit to the trouble bell bus 20 51' for completing a circuit to the trouble bell 102.

It will be seen from the foregoing that each fire signal is printed at the recorder; also that the designating numbers of the box transmitting 25 such fire signal are sounded on the general alarm bells 531, 581'. In the preferred arrangement of the system, fire signals are not arranged to cause actuation of the summary indicator, although they may be arranged to do so if de- 30 sired.

Supervisory signals denoting the condition of the equipment in the installation and denoting other supervisory conditions pertinent to fire prevention are printed at the recorder and are also caused to actuate the summary indicator, but preferably do not sound the general alarm bells 581, 581'. Referring now to the manner in which the selecting switch 416 causes such supervisory signals to actuate the summary indicator, it will be observed that following the first two switch contacts 416 and 416b, the alternate contacts 416c, 416e, etc., are multiplied together through a common conductor 601 and the intervening alternate series of contacts 416d, 416f, etc., are multiplied together through a second common conductor 602. This arrangement is merely illustrative and can be varied as desired. Wires 601' and 602' extend from these multiple conductors 601 and 602, respectively, to the two coils of the summary indicator. In the preferred arrangement disclosed the printing legends on the condition wheel 322 are so related that the type faces which designate trouble conditions alternate with the type faces that designate trouble-corrected or "O. K." conditions; also that when either of the former type faces designating trouble conditions is in a printing position the arm 416' of the selector switch 416 is in engagement with the corresponding one of the contacts 416d, 416f, etc., whereas when either of the latter type faces designating trouble-corrected conditions is in a printing position said arm 416' is in engagement with the corresponding one of the other alternate contacts 416c, 416e, etc. When the apparatus is arranged in this preferred relation the wire 601' is connected to the subtracting coil 518 of the summary indicator and the wire 602' is connected to the adding coil 517 thereof. Obviously, if it is desired to group the type faces on different portions of the condition wheel, or to reverse the alternating sequence thereof, this can be accommodated by appropriately changing the multiple conductors 601 and 602 or by changing the connections to the coils 518, 517. The selected one of said coils is adapted

to have positive polarity impressed thereon through the rotary switch 402 and selector switch 416, as I shall shortly describe.

The two negative terminals of both of said coils 517, 518 have connection with the negative oscillator bus 135, whereby during the signaling and recording operation negative impulses are being transmitted from the oscillator 114 down to the adding and subtracting coils 517 and 518. Neither one of these coils, however, is energized until near the end of the recording cycle. That is to say, irrespective of which one of the selector contacts 416b, 416c, etc., the selector switch arm 416' has come to rest on at the instant of completing the operation of setting up the condition wheel in any supervisory, watch or like recording cycle, there will be no energization of either coil 517, 518 of the summary indicator at that instant because the selector switch arm 416' is only receiving negative potential through the printing coils 441 at that time, and since the opposite terminals of the adding and subtracting coils 517 and 518 are then also receiving negative impulses from the oscillator no energization of the latter coils is possible. However, when the rotary switch 402 moves into closed circuit position at a point one step short of the completion of the recording cycle and transmits positive polarity to the positive terminal of the printing coils 441, this positive polarity is also transmitted through wire 427', clip 427, and selector switch arm 416' to the particular selector switch contact 416b-416m on which the switch arm is resting. This positive polarity will hence be transmitted down either through wire 601' or wire 602' to the subtracting coil or to the adding coil, resulting in the energization of the selected coil, with consequent movement of the indicating disc or like indicating means of the summary indicator. Whether the disc is actuated in an additive direction or in a subtractive direction depends upon whether the condition wheel of the recorder is in a position to print a trouble signal or a trouble-corrected signal, this determining whether the selector switch arm 416' is in position to transmit positive polarity down through wire 602' or down through wire 601'. Only one impulse is transmitted to the selected coil of the summary indicator for energizing the same, this occurring concurrently with the energization of the printing coils 441 of the recorder. At the conclusion of the recording cycle, the restoration of the condition wheel 322 to its normal position restores the selector switch arm 416' to its normal position.

Referring now to the reset or set-up relay 618, 55 this relay comprises the two pairs of normally open trouble contacts *b* and *l*, and also comprises a pair of normally closed contacts 619. One of the latter contacts always receives positive polarity from the positive battery bus *p*, and the other of said contacts is connected through wire 621 with one end of the relay winding. The other end of said winding is connected through wire 622 with the negative conductor *N* extending out over the box operating circuit from the negative line terminal *NL* at central station. This relay will remain energized with the contacts 619 closed as long as the system is in its normal condition with a continuous testing current flowing out over the negative conductor *n*, since this negative polarity feeds one end of the relay winding and positive polarity is fed to the other end of the relay winding through contacts 619 and wire 621. However, as soon as the transmission of negative polarity over the box operating circuit con- 70 75

ductor N is interrupted, as by the tilting of the mercury tube 116 of the oscillator 114 to its circuit opening position, the supply of negative polarity through wire 622 to the relay winding is 5 interrupted, and consequently the relay is de-energized and the contacts 619 are separated. The relay will remain deenergized during the entire signaling operation because the opening of the contacts 619 has broken the supply of positive polarity to the other end of the relay winding. The trouble bell signaling contacts b have the same previously described connection with the buses 51 and 51' so that the closing of these contacts energizes the trouble bell 102. The closing 10 of the other pair of contacts l completes a circuit from bus 51 through wire 624 to lamp 485 and back through wire 625 to the other power supply bus 52. As previously described, this lamp 485 is mounted in the base portion of the recorder 15 for illuminating the paper tape, and continues to burn during the entire signaling operation and until the reset relay 618 is reset to normal condition. This resetting operation is performed by the closing of a suitable momentary contact 20 switch 626 located at central station. One contact of this switch is connected with the positive battery bus p through wire 627 and the other contact of said switch is connected through wire 628 with the wire 621 which leads to the positive 25 end of the relay winding, whereby the momentary closing of this resetting switch at the completion of the signaling operation establishes a shunt across the relay contacts 619 and supplies positive polarity to the relay winding for locking 30 up the relay in an energized condition, in which condition it will remain until the start of the next signaling operation.

I am aware that a large number of modifications of the circuits and structures shown herein is possible without departing from the underlying principles of the present invention, and I therefore intend to be limited only as defined by the spirit and scope of the appended claims.

I claim:

1. A recorder comprising a plurality of type wheels, advancing pawls for advancing said type wheels, a cam shaft comprising means for holding all but one of said pawls in inoperative position, said cam shaft in progressive angular movement 45 selecting the pawls to be placed in operative position, a selecting coil, an armature responsive thereto, means for imparting motion from said armature to said cam shaft when said selecting coil is de-energized, a step-up coil, an armature 50 responsive thereto operatively connected to actuate said pawls to advance the type wheels selected by said cam shaft, holding pawls for holding said wheels in their advanced positions, printing mechanism for making the printing impression, a 55 printing coil for actuating said printing mechanism, a first control mechanism for normally retaining said holding pawls in their inoperative positions and for normally preventing operation of said cam shaft, means for releasing said first 60 control mechanism when said step-up coil is energized, a second control mechanism for normally preventing operation of said printing mechanism, means for changing the condition of said second 65 control mechanism after said cam shaft has been actuated through a predetermined motion, and means functioning after the operation of said printing mechanism for restoring said first and second control mechanisms to normal conditions.

2. A recorder comprising a plurality of type 75 wheels, advancing pawls for advancing said type

wheels, a cam shaft comprising means for holding all but one of said pawls in inoperative position, said cam shaft in progressive angular movement selecting the pawls to be placed in operative position, a selecting coil, an armature responsive thereto, means for imparting motion from said armature to said cam shaft, a step-up coil, an armature responsive thereto operatively connected to actuate said pawls to advance the type 10 wheels selected by said cam shaft, holding pawls for holding said wheels in their advanced positions, printing mechanism for making the printing impressions, a printing coil for actuating said printing mechanism, a control mechanism for normally retaining said holding pawls in their inoperative positions and for normally preventing operation of said cam shaft until after said step-up coil is energized, means for releasing said control mechanism when said step-up coil is energized, a switch in the circuit of said printing coil 15 responsive to the operation of said cam shaft, whereby a predetermined number of operations of said cam shaft said switch moves to closed circuit position, and means functioning after the operation of said printing mechanism for restoring said control mechanism to normal position.

3. A recorder comprising a plurality of type wheels, advancing pawls for advancing said type wheels, a cam shaft comprising means for holding all but one of said pawls in inoperative position, said cam shaft in progressive angular movement 20 selecting the pawls to be placed in operative position, a selecting coil, an armature responsive thereto, means for imparting motion from said armature to said cam shaft when said selecting coil is de-energized, a step-up coil, an armature responsive thereto operatively connected to actuate said pawls to advance the type wheels selected by said cam shaft, holding pawls for holding said wheels in their advanced positions, printing 25 mechanism for making the printing impression, a printing coil for actuating said printing mechanism, control means for normally retaining said holding pawls in their inoperative positions, a switch in the circuit of said selecting coil for normally retaining the circuit of said selecting coil open until after the initial energization of said step-up coil, means for releasing said control 30 means and for moving said switch to closed circuit position when said step-up coil is energized, a switch in the circuit of said printing coil responsive to the operation of said cam shaft, whereby after a predetermined number of operations of said cam shaft said switch moves to closed circuit position, and means functioning 35 after the operation of the printing mechanism for restoring said control means and said first named switch to normal position.

4. A recorder comprising a plurality of type wheels, advancing pawls for advancing said type 40 wheels, a cam shaft comprising means for holding all but one of said pawls in inoperative position, said cam shaft in progressive angular movement selecting the pawls to be placed in operative position, a selecting coil, an armature responsive 45 thereto, means for imparting motion from said armature to said cam shaft, a step-up coil, an armature responsive thereto operatively connected to actuate said pawls to advance the type wheels selected by said cam shaft, holding pawls 50 for holding said wheels in their advanced positions, printing mechanism for making the printing impression, a printing coil for actuating said printing mechanism, control means for normally retaining said holding pawls in their inoperative 55 positions.

positions, means for releasing said control means when said step-up coil is energized, a pair of concurrently actuated switches responsive to the operation of said cam shaft, whereby after a pre-determined number of operations of said cam shaft said switches move to closed circuit position, one of said switches being connected with said selecting coil and the other of said switches being connected with said printing coil, and 10 means functioning after the operation of said printing mechanism for restoring said control means to normal position.

5. In a recorder, the combination of a plurality of type wheels, advancing pawl means for actuating said type wheels, armature means for actuating said pawl means, advancing coil means for actuating said armature means, and selector mechanism for selecting said advancing pawl means comprising a cam shaft, and means operating to impart the same direction of motion to said cam shaft in all selecting and restoring operations of the recorder.

6. In a recorder, the combination of a plurality of type wheels, actuating mechanism for actuating said type wheels, a step-up coil for operating said actuating mechanism, selector mechanism for performing a selecting function with respect to said type wheels, said selector mechanism comprising a selecting coil, a switch for normally 25 maintaining the circuit of said selecting coil open when the recorder is not in operation, and means responsive to the initial energization of said step-up coil at the start of a recording cycle for moving said switch to closed position.

35 7. In a recorder the combination of a plurality of type wheels, advancing pawls for advancing said type wheels, an armature for actuating said advancing pawls, a step-up coil for actuating said armature, selector mechanism for performing a selecting function with respect to said type wheels, said selector mechanism comprising a selecting coil, said step-up coil being adapted to be energized in advance of said selecting coil at the start of a recording cycle, a switch for normally 40 maintaining the circuit of said selecting coil open when the recorder is not in operation, and means actuated by the initial movement of the armature of said step-up coil at the start of a recording cycle for moving said switch to closed 45 position.

8. In a recorder the combination of a plurality of type wheels, advancing pawl mechanism for advancing said type wheels, a step-up coil for actuating said advancing pawl mechanism, holding pawls for said type wheels which normally remain in inoperative positions when the recorder is not operating, selector mechanism for performing a selecting function with respect to said type wheels, said selector mechanism comprising a selecting coil, said step-up coil being adapted to be 10 energized in advance of said selecting coil at the start of a recording cycle, a switch for normally maintaining the circuit of said selecting coil open when the recorder is not in operation, and means whereby the initial impulse transmitted to said 15 step-up coil at the start of a recording cycle performs the three functions of advancing one of the type wheels through said advancing pawl mechanism, releasing said holding pawls whereby they become effective to hold said type wheels in 20 their advanced positions, and moving said switch to closed position.

9. In a recorder, the combination of a plurality of type wheels, actuating mechanism for actuating said type wheels, a step-up coil for operating 25 said actuating mechanism, selector mechanism for performing a selecting function with respect to said type wheels, said selector mechanism comprising a selecting coil, a switch for normally maintaining the circuit of said selecting coil open 30 when the recorder is not in operation, printing mechanism comprising a printing coil, means responsive to the initial energization of said step-up coil at the start of a recording cycle for moving said switch to closed position, and means responsive to the deenergization of said printing coil at the end of a recording cycle for moving 35 said switch back to open position.

10. In a recorder, the combination of a plurality of type wheels, actuating mechanism for said type 40 wheels comprising a step-up coil, selector mechanism for said type wheels comprising a selecting coil, printing mechanism comprising a printing coil, a switch controlling the circuit of said selecting coil, and means responsive to said step-up coil 45 for moving said switch to one position and responsive to said printing coil for moving said switch to another position.

JAMES R. HARRINGTON. 50

CERTIFICATE OF CORRECTION.

Patent No. 2,202,853.

June 4, 1940.

JAMES R. HARRINGTON.

It is hereby certified that error appears in the printed specification of the above numbered patent requiring correction as follows: Page 15, second column, line 22, claim 2, before "a" insert the word --after--; and that the said Letters Patent should be read with this correction thereon that the same may conform to the record of the case in the Patent Office.

Signed and sealed this 9th day of July, A. D. 1940.

(Seal)

Henry Van Arsdale,
Acting Commissioner of Patents
